INVENTOR.
C. L. Ball

BY *Benj. W. Dutton*
ATTORNEY

UNITED STATES PATENT OFFICE.

CECIL L. BALL, OF STOCKTON, CALIFORNIA.

GAME SCORE BOX.

Application filed June 9, 1923. Serial No. 644,370.

To all whom it may concern:

Be it known that I, CECIL L. BALL, a citizen of the United States, residing at Stockton, county of San Joaquin, State of California, have invented certain new and useful Improvements in Game Score Boxes; and I do declare the following to be a full, clear, and exact description of the same, reference being had to the accompanying drawings, and to the characters of reference marked thereon, which form a part of this application.

This invention relates to a device for keeping and indicating the score between two teams participating in a game, the principal object of the invention being to provide a device especially adapted for use in gymnasiums and the like, to keep the scores of such games as are played therein, such as basketball, indoor baseball, volley and hand ball, and the like, in such a manner that the score may be easily seen by both the players and the onlookers.

Another object is to provide a device of this character so constructed that the score keeper may stand behind the device at all times, so as not to ever shut off the view of the score from those desiring to see the same, and yet may know, without himself seeing the main score-figures, that they are correctly displayed.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective view of the score box.

Fig. 2 is a front view of the same, with the front cover and score-ribbons removed.

Fig. 3 is a cross section on the line 3—3 of Fig. 2, with all members in place.

Fig. 4 is a fragmentary portion of a score ribbon.

Referring now more particularly to the characters of reference on the drawings, the numeral 1 denotes a box or container of suitable size, having a front cover 2 provided with horizontally spaced openings 3, prefer-

ably rectangular in shape and located between the top and bottom of the cover.

Smaller orifices 4 are cut through the top of the box adjacent the side edges thereof, or beyond the plane of the corresponding edges 60 of the openings 3.

The box has a vertical partition 5 between the openings 3, dividing the box into two compartments. In the side walls of each compartment are journaled upper and lower spools 6 and 7, each pair being independent of the other but arranged in common horizontal alinement.

The upper spools 6 are turned by means of knobs 8 on the outside of the box, while the lower spools 7 may be turned by crank handles 9 similarly located.

A ribbon or strip 10 of any suitable material is secured at its ends to each pair of vertically spaced spools and is wound thereon, being arranged so as to be unwound from one spool while being wound onto the other.

These ribbons, intermediate their connection with their respective spools, passes around rollers 11 located close to the cover 2 and adjacent the upper and lower ends thereof, so as to throw the ribbons close against the openings 3 and also close to the orifice 4 at all times.

The ribbons bear numbers 12, nearly the height of the openings 3, running from 1 up to whatever high number is desired as the limit, said numbers being so spaced apart longitudinally of the ribbons that no part of adjacent numbers projects into view 90 through said openings when a certain number is being displayed.

The ribbons also have another set of smaller numbers 13, corresponding to the numbers 12, but arranged to one side of the same, so as never to be visible through the openings 3 but in alinement only with the orifices 4. These smaller numbers are spaced apart from center to center a distance equal to the corresponding spacing of the numbers 12, but are inverted relative thereto, so that to a scorekeeper standing behind the box as preferably intended he should, these small numbers, visible to him through the orifices 4, will be right side up.

The numbers 13 are not of course in horizontal alinement with the main numbers 12, but are spaced vertically from the corresponding main numbers a distance equal to that between the orifices 3 and 4, so that 110

when "1" for instance is displayed at the opening 3, "1" will also be seen below the orifice 4.

The numbers are arranged on the ribbons 5 so that they are raised to advance the score, and are then being wound onto the upper spools 6 by turning of the relatively slow-action knobs 8.

When the game is ended, the lower spools 10 are turned to retract the ribbons, the crank handles 9 employed on the lower spools enabling faster rotative movement thereof being had.

From the foregoing description it will 15 be readily seen that I have produced such a device as substantially fulfills the objects of the invention, as set forth herein.

While this specification sets forth in detail the present and preferred construction 20 of the device, still in practice such deviations from such detail may be resorted to as do not form a departure from the spirit of the invention, as defined by the appended claim.

Having thus described my invention what 25 I claim as new and useful and desire to secure by Letters Patent is:

A game score device comprising a box having an opening in front, a ribbon inside the box movable across and adjacent the top of the box, spaced spools on which the ribbon is wound, there being an opening in said top above the adjacent spool, and an idler roller adjacent and under said top opening and over which the ribbon passes intermediate the upper spool and the front opening of the box, whereby to maintain the ribbon in close proximity to the top opening regardless of the amount of ribbon on the spool; said ribbon having two corresponding sets of numbers on the same face thereof, the numbers of one set being visible only through the front opening and the others only through the top opening and in correlating order.

In testimony whereof I affixed my signature.

CECIL L. BALL.
